Primary Examiner — Anhdao Doan*Assistant Examiner* — John R Yeh(74) *Attorney, Agent, or Firm* — Dority & Manning, P.A.(57) **CLAIM**

The ornamental design for a bottle wash clip, as shown and described.

DESCRIPTION

FIG. 1 is a perspective view of a bottle wash clip.

FIG. 2 is a rear view of the bottle wash clip.

FIG. 3 is a front view of the bottle wash clip.

FIG. 4 is a side view of the bottle wash clip.

FIG. 5 is another side view of the bottle wash clip.

FIG. 6 is a top view of the bottle wash clip; and,

FIG. 7 is bottom view of the bottle wash clip.

In the drawings, dashed lines depict environmental structure that forms no part of the claimed design.
